Primary Examiner—Raphael Barkai
Attorney, Agent, or Firm—Katherine McGuire**[57] CLAIM**

The ornamental design for eyewear temple, as shown and described.

DESCRIPTION

FIG. 1 is an elevational view of an eyewear temple of my new design showing the side thereof facing away from the wearer's head;

FIG. 2 is an elevational view of the opposite side of the view of FIG. 1 (i.e., the side thereof facing toward the wearer's head);

FIG. 3 is a bottom plan view thereof;

FIG. 4 is a top plan view thereof;

FIG. 5 is a front perspective view thereof; and,

FIG. 6 is a rear perspective view thereof.

The dashed lines appearing in FIGS. 1-2, and 5-6 are for environmental purposes only and form no part of the claimed design.
